Primary Examiner—Ruth McInroy

(57) **CLAIM**

The ornamental design for a mouthguard, as shown and described.

DESCRIPTION

FIG. 1 is a top plan view of a first embodiment of a mouthguard showing our new design;

FIG. 2 is a bottom plan view thereof;

FIG. 3 is a front elevational view thereof;

FIG. 4 is a rear elevational view thereof;

FIG. 5 is a right side elevational view thereof, the left side being a mirror image;

FIG. 6 is a top plan view of a second embodiment thereof;

FIG. 7 is a bottom plan view of FIG. 6;

FIG. 8 is a front elevational view of FIG. 6;

FIG. 9 is a rear elevational view of FIG. 6; and,

FIG. 10 is a right side elevational view of FIG. 6, the left side being a mirror image.
